COMBINED HANDLE AND CONTROL ASSEMBLY
FOR A TELEVISION RECEIVER CABINET

Edward Westervelt, Glen Ellyn, Ill., assignor to Motorola,
Inc., Chicago, Ill., a corporation of Illinois

Application July 26, 1957, Serial No. 47,096

Term of patent 14 years

(Cl. D56—4)

Fig. 1 is a perspective view of a combined handle and control assembly for a television receiver cabinet, showing my new design;

Fig. 2 is a front elevational view;

Fig. 3 is a top plan view of Fig. 2;

Fig. 4 is a rear elevational view thereof;

Fig. 5 is a side elevational view looking in the direction of the line 5—5 of Fig. 4; and

Fig. 6 is a sectional view along the line 6—6 of Fig. 4.

The broken line showing of a television cabinet is for illustrative purposes only.

I claim:

The ornamental design for a combined handle and control assembly for a television receiver cabinet, as shown and described.
